ELECTRIC KNIFE HANDLE

Jerold R. Peterson, Roselle, Ill., assignor to Sunbeam Corporation, Chicago, Ill., a corporation of Illinois

Filed May 25, 1965, Ser. No. 85,445

Term of patent 14 years

(Cl. D22—3)

FIG. 1 is a perspective view of an electric knife handle embodying my new design the broken line showing of the knife blade being for purposes of illustration only;

FIGS. 2 and 3 are top and bottom plan view, respectively, on an enlarged scale thereof; and

FIGS. 4, 5 and 6 are side, front and rear elevational views, respectively, thereof.

I claim:

The ornamental design for an electric knife handle, as shown and described.
